UNITED STATES PATENT OFFICE.

ARTHUR GODFREY, OF CHICAGO HEIGHTS, ILLINOIS.

GLASS-WORKING MACHINE.

987,714.

Specification of Letters Patent. Patented Mar. 28, 1911.

Application filed June 2, 1910. Serial No. 564,682.

To all whom it may concern:

Be it known that I, ARTHUR GODFREY, a citizen of the United States, residing at Chicago Heights, county of Cook, and State 5 of Illinois, have invented certain new and useful Improvements in Glass-Working Machines, of which the following is a specification.

My invention relates to glass-working 10 machines and more specifically to that class thereof designed for employment especially in the manufacturing of bottles.

The object of my invention is the provision of a machine of the character mentioned by means of which bottles of perfect 15 form may be made with ease and expedition.

A further object is the provision of a glass-working machine as mentioned which will be of durable and economical construction and efficient in operation.

Other objects will appear hereinafter.

With these objects in view my invention consists in a glass-working machine characterized as above mentioned and in certain 25 details of construction and arrangement of parts all as will be hereinafter fully described and more particularly pointed out in the appended claims.

My invention will be more readily understood by reference to the accompanying drawings forming a part of this specification, and in which,

Figure 1 is a central vertical longitudinal section of a glass-working machine embodying the preferred form of my invention, Fig. 2 is a vertical section at right angles to Fig. 1, and Figs. 3 and 4 are slightly enlarged transverse sections taken on lines x—x and y—y respectively of Figs. 1 and 2.

Referring now to the drawings 1 indicates the supporting frame of the device which is suitably mounted upon wheels 2, whereby ready transportation thereof may be effected. The frame 1 comprises an upper horizontal table 3 and a lower parallelly extending table 3', said tables 3 and 3' being spaced at and rigidly secured together by posts 4 and braces 4'. Arranged substantially centrally upon the upper side of 40 the table 3 is a metallic disk 5. Having its base rigidly secured to said disk is an upwardly extending post 6. Rotatably mounted upon the upper reduced end portion of said post are the slotted lugs 7 of 45 the similar parts 8 and 9 of the mold 10. The latter is of cylindrical exterior form,

the interior thereof comprising the upper enlarged portion 11 which is adapted to form the body of the bottle, and the lower reduced neck-forming portion 12. Formed 50 upon the outer surface of the mold part 8 adjacent the outer longitudinal edge thereof are vertically alining lugs 13 in which is pivotally secured a locking member 14, 15 indicating the operating handle 65 therefor. The offset outer end of said lever is adapted to engage a lug 16 formed upon the mold part 9 adjacent the outer longitudinal edge thereto, and whereby said mold parts 8 and 9 may be securely locked 70 in closed position. Projecting from the mold part 9 is a handle 17, by means of which and the handle 15 of the member 14 said mold parts may be readily swung apart when the same are unlocked. 75

The upper end of the mold 10 is open for the reception of the cylindrical blank-forming member 18 which is mounted for co-axial movement with said mold. Formed centrally through the member 18 is a bore 80 19 which is adapted to register with the reduced portion 12 of said mold. The guide 20 of the bore 19 is flared or enlarged, as clearly illustrated, to facilitate pouring of molten glass into said bore. 85

The upper end of the member 18 is secured in the upper end of a substantially rectangular frame 21, the vertically disposed parallelly extending bars 22 of the latter being slidably mounted in tubular guides 23 90 arranged upon the table 3, said bars 22, as seen, also projecting through the latter. Mounted upon the table 3' co-axially with the mold 10 is a cylinder 24. Operating in said cylinder is a piston 25 and a piston rod 26. The upper end of the piston rod 26 projects exteriorly of the cylinder 24 into close proximity with the lower transverse bar 28 of the frame 21, the upper extremity 95 of said piston rod being bifurcated as at 27 for the reception of said bar. The arrangement is such that, when the piston 25 and hence the piston rod 26 is at its upper terminal of movement the member 18 will be elevated above the mold 10 so that the lower 100 extremity thereof will be positioned slightly above the upper extremity of said mold. Communicating with the upper extremity of the cylinder 24 is a pipe 29 and communicating with the lower extremity of said cylinder a pipe 30; the outer ends of said pipes 29 and 30 being connected with a com- 110

pressed air supply pipe 31, the latter being connected with any suitable source of compressed air supply. A two-way valve 32 is provided at the junction of the pipes 29 and 30 with the pipe 31, 33 indicating the operating hand-piece of said valve. With this arrangement, it will be seen that in order to effect the vertical movement of the piston 25 and hence the elevation of the member 18, it is only required to operate the hand-piece 33 to open the passage from the pipe 31 to the pipe 30. When it is desired to lower said piston said handle 33 needs only to be operated to establish a connection between the pipe 29 and the pipe 31. When this is done, the piston 25 and hence the piston rod 26 will evidently be forced to its lower terminal of movement. When said piston rod is lowered the member 18 will drop by gravity to its normal position within the mold 10.

Secured to the upper end of the mold part 8 is a channel guide 34 in which is slidably mounted a closure 35 which is adapted by means of a handle 36, when the member 18 is in elevated position, to be slid into position to close the upper extremity of the mold.

Slidably mounted in the table 3 and the member 5 co-axially with the mold 10 is a tube 37. The lower extremity of the tube 37 is secured to a cross piece 38. The extremities of the cross piece 38 are slotted for the reception of guide rods 39, downward movement of said cross pieces and hence the tube 37 being limited by nuts 39' threaded upon the lower extremities of said rods 39. Compression springs 40 interposed between the ends of the cross piece 38 and the table 3 are adapted to normally hold the former and hence the tube 37 at its lower extremity of movement.

41 indicates a lever the rearward extremity 42 of which is fulcrumed to a depending post 43 secured to the under side of the table 3. Said lever is provided with an elongated slot 44 which is engaged by a pin 45 carried in a bifurcated lug 46 depending from the cross piece 38. Thus an operative connection between the tube 37 and the lever 41 is established, vertical movement of said tube being, with the construction described, effected by oscillating said lever. Communicating with the tube 37 adjacent its lower extremity is a flexible pipe or hose 47 which is connected at its outer extremity to the compressed air supply pipe 31. The passage through the pipe 47 is controlled by a valve 48, 49 indicating the operating handle of said valve.

The operation of the device is as follows: With the blank-former 18 at its lowermost position, that is within the mold 10, the proper quantity of molten glass is poured into said blank-former, a portion of this

glass flowing down into the reduced portion 12 of the mold to form the neck of the bottle. The tube 37 is then, by means of the lever 41, forced upwardly into the molten glass blank contained in the member 18, to the position indicated in dotted lines in Figs. 1 and 2, to form the passage through the neck of the bottle. The member 18 is now elevated, such elevation being effected, as before stated, by simply operating the valve 33 to open the passage to the pipe 30. The closure 35 is now slid to closing position over the upper end of the mold. Through the medium of the valve 48 air under pressure is then blown through the tube 37 effecting the blowing of the glass blank into the form of the interior surface of the mold. Owing to the fact that tube 37 is open at the top and extends into the mold and blank only to the depth of the neck of the bottle, the portions of glass to be moved farthest by the air admitted through said tube lie immediately above the opening in said tube, whereby they are directly affected by the incoming air for elevation and detachment from said tube. Thus the bottle is formed. Upon being sufficiently cooled the finished bottle may be readily removed after lowering the tube 37, disengaging the locking member 14, and swinging the mold parts 8 and 9 apart.

With the construction disclosed it will be seen that a machine of durable and economical design is provided, and one by means of which bottles may be made with great rapidity, it being evident that, with one familiar with devices of this nature operating the machine, the operations above enumerated may be executed in quick succession.

While I have shown what I deem to be the preferable form of my glass-working machine I do not wish to be limited thereto as there might be various changes made in the details of construction and arrangement of parts described without departing from the spirit of the invention comprehended within the scope of the appended claims.

Having described my invention what I claim as new and desire to secure by Letters Patent is:

1. In a glass vessel forming machine, the combination of a supporting frame comprising an upper and lower table; a vertically disposed mold mounted upon said upper table, said mold being open at its upper end, the same being formed of two swingingly connected parts; a vertically reciprocable tubular blank-former movable into and out of said mold through said open upper end; a cylinder coaxial with said mold mounted upon said lower table; a piston and a piston rod operating in said cylinder, the said piston rod being bifurcated at its upper end; tubular guides mounted upon said upper table at each side of said mold; operating

bars extending through said guides and upper table and having their upper ends connected with said blank-former; a cross bar connecting the lower ends of said bars and arranged to be engaged by the bifurcated end of said piston rod; compression air connections with the opposite ends of said cylinder; means for controlling the flow of air to said cylinder; a movable closure for the upper end of said mold; a vertically reciprocable compression air tube open at its top and arranged to reciprocate into the bottom of said mold; means for elevating said tube into said mold; and means for controlling the flow of air to said tube, substantially as described.

2. In a glass vessel forming machine, the combination of a supporting frame comprising an upper and lower table; a vertically disposed mold mounted upon said upper table, said mold being open at its upper end, the same being formed of two swingingly connected parts; a vertically reciprocable tubular blank-former movable into and out 25 of said mold through said open upper end; a cylinder coaxial with said mold mounted upon said lower table; a piston and a piston rod operating in said cylinder, said piston rod being bifurcated at its upper end; tubu-

lar guides mounted upon said upper table at 30 each side of said mold; operating bars extending through said guides and upper table and having their upper ends connected with said blank-former; compressed air connections with the opposite ends of said cylinder; means for controlling the flow of air to 35 said cylinder; a movable closure for the upper end of said mold; a vertically reciprocable compression air tube open at its top and arranged to reciprocate into the bottom 40 of said mold; a cross bar secured to the lower end of said tube; vertical guide rods secured to the ends of said tube cross bar and passing through guide openings provided in said upper table; compression springs on 45 said guide rods between said cross bar and the bottom of said upper table; a lever connected to elevate said tube; and means for controlling the flow of air to said tube, substantially as described.

In testimony whereof I have signed my name to this specification in the presence of two subscribing witnesses.

ARTHUR GODFREY.
